CARTON

William T. Stearn, Cumberland, Md., assignor to
Celanese Corporation of America, a corpora-
tion of Delaware

Application October 21, 1948, Serial No. 55,670

2 Claims. (Cl. 229—45)

1

This invention relates to cartons, and relates more particularly to cartons for packing cones or cheeses of yarn.

An object of this invention is to provide a carton for cones or cheeses of yarn which will protect the same during the shipping or storing thereof.

Another object of this invention is the provision of an improved carton that is easy to manufacture, readily filled and quickly taken apart, collapsed and made ready for return.

Still another object of this invention is to provide a collapsible partition carton which after it is filled and closed maintains a fully closed order without the use of staples, adhesive tape or similar expedients.

Other objects of this invention, together with certain details of construction and combinations of parts, will appear from the following detailed description and drawing.

In the drawing, wherein a preferred embodiment of my invention is shown,

Fig. 1 is a plan view of the carton blank construction in accordance with my invention,

Fig. 2 is a plan view showing the carton blank with certain sections thereof folded and arranged to form partitions of the yarn package,

Fig. 3 is a plan view of the carton blank showing the partition cones of yarn partially enclosed, and

Fig. 4 is a plan view of the yarn package ready for shipment or storage.

Like reference numerals indicate like parts throughout the several views of the drawing.

Referring to the drawing, the blank shown in Fig. 1 and generally indicated by reference numeral 5 is adapted to be folded and set up to form the carton shown in Fig. 4. The present carton is particularly useful for the packing and shipping of cones or cheeses of yarn, since such yarn packages may be held therein in such a manner that they cannot rub against each other. The necessity for holding the yarn packages clear of contact with each other will be quite obvious when consideration is given to the fact that a yarn package, such as a cone or cheese, contains a single continuous length of yarn which is delicate and, therefore, extremely susceptible to damage by abrasion. Yarn damaged in transit results in machine stoppages in subsequent warping and knitting operations, causing imperfect fabric and financial loss. Moreover, the present carton is so designed that a minimum of waste is produced in its fabrication, and its arrangement is such that

2

it may readily be folded into proper form to receive the yarn packages.

The blank 5 may be cut from any suitable sheet material such as corrugated board, cardboard, thin metal or the like in any convenient manner, as by a die of the desired configuration. The required fold-lines may be supplied to the blank during the cutting operation or in a subsequent operation, which operations are well known in the art.

The blank 5 comprises a rectangular portion 6, forming the bottom of the carton, delineated by fold-lines 7, 8, 9 and 11. Integral with rectangular portion 6 at fold-lines 7 and 9 are two sections 12 and 13, respectively, and integral with rectangular portion 6 at fold-lines 8 and 11 are sections 14 and 15, respectively. The sections 12 and 13 being separated from sections 14 and 15 by cut-out portions or slots 16.

Sections 12 and 13 are similar in configuration and are each provided with fold-lines 17, 18, 19 and 21, dividing each of said sections 12 and 13 into five substantially equal portions 22, 23, 24, 25 and 26. Section 14 is provided with fold-line 27 dividing the same into two portions, intermediate portion 28 and end portion 29. The latter portion is provided with three circular openings 31, which are of the same diameter as circular openings 32 formed in bottom 6, and rectangular openings 33. Section 15 is provided with a fold-line 34 dividing the same into an intermediate section 35 and an end section 36. Circular openings 37 of smaller diameter than openings 31 and 32 are provided in end section 36, as well as rectangular openings 38. Integral with one side 39 of each of openings 38 is a tab 40 provided with fold-line 41. Two smaller rectangular slots 42 are formed in end section 36 substantially along the fold-line 34.

To pack cones of yarn in a carton, the sections 12 and 13 are bent upwards along fold-lines 7 and 9, respectively, and then each of the sections is bent along fold-lines 17, 18, 19 and 21 to form compartments 43 and 44. Between compartments 43 and 44 there is a space sufficient to form a third compartment 45. The compartments are all of substantially the same size and large enough to receive a package of yarn such as a cone 46 with space to spare. The central portions 24 of sections 12 and 13 form the end walls of the carton. After the compartments are formed, cones 46 are placed therein, the cores of the cones being inserted in openings 32 of the bottom sections 6. After the cones are placed in their respective compartments, section 15 is bent along

fold-line 11 and thus the intermediate section 35 forms the side wall of the carton. The section 15 is also bent along fold-line 34 so that the end section 36 forms one of the tops of the carton. The holes 37 in section 36 slip over the tops of the cores of the cones thereby holding the latter in rigid position so as to prevent damage to the said cones. Next, the section 14 is bent along fold-lines 8 and 27, intermediate section 28 forming the side wall of the carton and section 29 forming the top. In this position of the end section 29 openings 31 register with openings 37 and openings 33 register with openings 38. Then tabs 40 are pulled through openings 33, bent along fold-line 41 and the ends of the bent tabs located in slots 42. The carton is now securely fastened holding the product substantially firmly without the use of adhesive tape or other expedients.

When packing a number of cartons in a large shipping box, the individual cartons containing three cones are stacked 3, 4 or more in vertical alignment. For this reason, the holes in section 29 are made larger than holes 37 in section 36 so that when stacking the cartons the base of the cores of the yarn cones in the upper carton locate in openings 31 and are, therefore, positively held and, moreover, the vertical space requirements are reduced.

When the carton is received by the consignee and the cones of yarn removed, the carton readily folds down to its original flat form as shown in Fig. 1. Accordingly, it can, therefore, be easily packed and returned to the cone manufacturer with a minimum of space requirement.

It is to be understood that the foregoing detailed description is given merely by way of illustration and that many variations may be made therein without departing from the spirit of my invention.

Having described my invention, what I desire to secure by Letters Patent is:

1. A carton for the reception of yarn packages comprising a rectangular bottom portion, a section folded to form the sides and covers of the cartons attached to each longitudinal edge of said bottom portion, and a section attached to each of the lateral edges of said bottom portion, each of said latter sections being folded to form an end wall of said carton and a fully walled compartment, the compartments being spaced

with respect to one another to form therebetween a space walled on two sides only, the first mentioned sections when folded to operative position form with said space a fully walled compartment, said bottom portion and said covers having openings therein forming a plurality of series of openings, the openings of each series being in alignment when the carton is in closed order and cooperate to maintain a yarn package in predetermined position in the carton.

2. A carton for the reception of yarn packages comprising a rectangular bottom portion, a section folded to form the sides and covers of the cartons attached to each longitudinal edge of said bottom portion, and a section attached to each of the lateral edges of said bottom portion, each of said latter sections being folded to form an end wall of said carton and a fully walled compartment, the compartments being spaced with respect to one another to form therebetween a space walled on two sides only, the first mentioned sections when folded to operative position form with said space a fully walled compartment, said bottom portion and said covers having circular openings therein forming a plurality of series of openings, the openings of each series being in alignment when the carton is in closed order and cooperate to maintain a yarn package in predetermined position in the carton and means in said covers of the carton cooperating to maintain the carton in closed order, said means comprising rectangular openings in one of said covers and tabs and notches in the other of said covers.

35 WILLIAM T. STEARN.
